(57) **CLAIM**

The ornamental design for a gaming machine, as shown and described.

DESCRIPTION

FIG. 1 is a front perspective view of a gaming machine showing our design according to a first embodiment; FIG. 2 is a front elevation view thereof; FIG. 3 is a rear elevation view thereof; FIG. 4 is a right side elevation view thereof; FIG. 5 is a left side elevation view thereof; FIG. 6 is a top plan view thereof; FIG. 7 is a front perspective view of a gaming machine showing our design according to a second embodiment; FIG. 8 is a front elevation view thereof; FIG. 9 is a rear elevation view thereof; FIG. 10 is a right side elevation view thereof; FIG. 11 is a left side elevation view thereof; FIG. 12 is a top plan view thereof; FIG. 13 is a front perspective view of a gaming machine showing our design according to a third embodiment; FIG. 14 is a front elevation view thereof; FIG. 15 is a rear elevation view thereof; FIG. 16 is a right side elevation view thereof; FIG. 17 is a left side elevation view thereof; and, FIG. 18 is a top plan view thereof.

The dashed broken lines in the drawings illustrate portions of the gaming machine that form no part of the claimed design.
